UNITED STATES PATENT OFFICE.

JULIUS O. ROBERTS, OF ABILENE, KANSAS.

TOOL.

1,333,778.

Specification of Letters Patent. Patented Mar. 16, 1920.

Application filed November 10, 1919. Serial No. 337,005.

To all whom it may concern:

Be it known that I, JULIUS O. ROBERTS, a citizen of the United States, residing at Abilene, in the county of Dickinson and 5 State of Kansas, have invented a new and useful Tool, of which the following is a specification.

This invention relates to tools and more especially to an improved device for removing or pulling cotter pins or gib keys from a shaft aperture or the like in which the pin is engaged to serve its usual function to retain parts in assembled relation.

The invention has for a further object, 15 the provision of a very simple and extremely effective tool of the above class, which can be very economically manufactured and which serves to drive or pull out the cotter pin or gib key, instead of the usual operation of extracting the same as is common in the art, and which requires unusual strength to obviate complication of structure, and provide a thoroughly practical tool, which permits its use in places where 20 a prying device or straight tool cannot be used, and which is strong and durable.

With the above objects and others in view as will appear as the description proceeds, the invention comprises certain novel combinations and arrangements of parts as will be hereinafter more particularly pointed out and claimed, it being understood that certain modifications and minor changes may be made or resorted to within the scope 35 of the claims, and as defined thereby, without departing from the spirit of the invention.

In the accompanying drawings;

Figure 1 is a perspective view showing 40 my improved tool in use, and

Fig. 2 is a perspective view of the tool.

Referring to the drawings in detail, in which like reference characters designate corresponding parts throughout the several 45 views, my improved cotter pin or gib key removing tool is shown as comprising a body 10 of drill-like construction, and comprising a uniformly tapered elongated member, of suitable cross-section. This body 50 is preferably uniformly tapered throughout its length, and is shown of polygonal or substantially round or circular cross-section, with the upper, driving or head end thereof as indicated at 11, larger than the opposite end which is adapted to engage the pin

at the loop thereof, or other similar member to be removed.

The end 11 is also shown extending at right angles to the axis of the tool and flat, though it is to be understood that I do not 60 wish to limit myself to this precise construction, and that the said end or driving head may be made of any suitable configuration. The end opposite the driving head, that is, the small or engaging end which is adapted 65 to engage the pin or key, is indicated at 12, said end being relatively tapered or pointed as indicated at 13, with the end beveled if desired, while the said end is curved or bent at an angle as shown at 14, not abruptly as 70 would likely break or fracture the metal, but gradually and at an obtuse angle to the main or shank portion.

The purpose of the bend is clearly shown in Fig. 1 of the drawings, as distinguished 75 from Fig. 2 of the drawings showing the device on an enlarged scale slightly in perspective, is to permit the device to be engaged around or between objects in the use of the device. As illustrative, there is 80 shown a frame member or bearing 15 in which is held a bolt 16 by a lock nut 17 having a series of spaced projections producing slots or recesses 18 between which is engaged a cotter pin or gib key 19 after 85 passing through a transverse opening or aperture through said bolt. In this position, the free ends of the legs of the cotter pin project from the periphery of the nut, as does the loop or eye 20 forming the head 90 of the cotter pin. Thus, the pointed or tapered end of the device is inserted in the loop at the proper angle, preferably at right angles thereto, or tangentially to the nut, and by hitting or striking the same a blow 95 with an object such as a hammer 21, by hand, upon the driving end or head, the pin will be easily, effectively and readily dislodged.

The tool is not used to pry the cotter- 100 pin or key out, as numerous other devices for extracting purposes, and the advantage of the device over all others, is the fact that this device will take out a cotter-key in any place no matter how difficult and in- 105 accessible it may seem to be, by slipping the tool against the head of the cotter-key and giving it a few taps with a hammer or any object, as shown in Fig. 1 of the drawings. Also, after the tool is driven into the head 110

of the cotter-pin, the latter will not slip up on the tool or keep spreading, but cling tight to the tool and thereby takes the pin or key out on the end of the tool and then 5 with another tap of the hammer, the key is off of the tool. Furthermore, it has nothing to get out of repair, as has the devices heretofore patented. One does not need any extra strength to use this tool as with the 10 usual methods or extractors and in inaccessible places, and the length can be varied and the device used where a straight tool cannot be used, also as a pinch bar for prying purposes and so forth. It is also noted 15 that when the device is in use, the end 12 will extend through the eye at right angles and the bar will extend substantially at right angles to cause the removing force to be exerted lengthwise of the pin.

20 Having thus described my invention, what I claim is:

1. A tool for removing cotter pins, gib keys or the like comprising a tapered body or bar having one end thereof of less degree 25 of taper and extended at a continuous curved angle at obtuse angles to the body.

2. A tool for removing cotter pins, gib keys or the like comprising a uniformly

tapered rectilinear body having one end thereof of less degree of taper and curved 30 at obtuse angles with respect to the body, the curvature of said end being continuous and on the same arc throughout.

3. A tool of the class described, comprising a tapered bar of substantially round 35 cross-section, having one end at the smallest portion of its cross-section, bent in a uniform curve at an obtuse angle relative to the main portion of the bar.

4. A tool of the class described, comprising a bar tapered throughout its length to provide a large driving head and hand hold therebeneath, the opposite end of the bar being substantially of pointed formation 45 for engagement with the eye of a cotter key or the like, and directed in curved angular formation relative thereto, substantially in the manner as and for the purposes specified.

In testimony that I claim the foregoing 50 as my own, I have hereto affixed my signature in the presence of two witnesses.

JULIUS O. ROBERTS.
